(57)

CLAIM

The ornamental design for an earphone, as shown and described.

DESCRIPTION

1. Earphone
2. Earphone
- 1.1 : Front
- 1.2 : Back
- 1.3 : Left
- 1.4 : Right
- 1.5 : Top
- 1.6 : Bottom
- 1.7 Left Perspective
- 2.1 : Front
- 2.2 : Back
- 2.3 : Left
- 2.4 : Right

(Continued)

2.5 : Top

2.6 : Bottom

2.7 Left Perspective

1 Claim, 14 Drawing Sheets
